UNITED STATES PATENT OFFICE.

JOHAN ALBERT HOËG, OF CHRISTIANIA, NORWAY.

DISTRIBUTING-BOX FOR POWDERS.

SPECIFICATION forming part of Letters Patent No. 678,400, dated July 16, 1901.

Application filed March 6, 1901. Serial No. 50,218. (No model.)

To all whom it may concern:

Be it known that I, JOHAN ALBERT HOËG, a subject of the King of Sweden and Norway, residing at Christiania, Norway, have invented certain new and useful Improvements 5 in Distributing-Boxes for Powders, of which the following is a specification.

In the treatment of many diseases it has often been desirable or necessary to apply a 10 powder to a certain place which is not readily accessible—for instance, by diseases in the throat or in all deeply-lying organs. The apparatus hitherto in use for this purpose have all, more or less, had the character of a pepper- 15 box, and the result has been that the powder has been distributed on a larger surface and in greater quantity than desired, whereby much powder was wasted, and as a result of the form of the apparatus it was nearly im- 20 possible to get a small portion of the powder just on the spot where it was intended to act.

I have therefore constructed a really effective and practical device, which is shown in the annexed drawing.

25 The device consists of two receptacles placed one inside the other, the outer receptacle being in two parts, forming a box embracing and inclosing the inner receptacle, which latter receptacle is open at one end and tapered at the other and perforated at the end of the taper.

In the drawing the figure is a vertical transverse cross-section through the device.

When the device is used, the inner receptacle or body B B' is filled with powder and placed in the part A of the outer receptacle, with its open end fitting against a washer c, of suitable material, placed in the bottom of the part A. The parts A and B of the two 35 receptacles fit closely together, so that no powder or other material in the inner receptacle can escape between the walls. The perforated point b of the receptacle B B' is now directed against the spot where it is de- 40 sired to apply the powder and by knocking on the bottom a of the part A the powder is exhausted through the perforation b in the part B', and according to the position given to the point of the cone B', nearer to or far- 45 ther from the spot where the powder shall

be applied, this will be concentrated or spread over a larger surface. The quantity of powder exhausted is regulated by the number and the force of the knocks. The cone B' 55 may be more or less long, so that its point may be introduced in parts of the human body which are not readily accessible, and the dimensions and form of the device may vary to suit the different use for which it is intended.

60 It is evident that by the use of my device, which is very economical as regards consumption of powder, the desired quantity may be applied on any spot, concentrated or spread, according to the distance between the point 65 of the cone and the spot where the powder has to be applied and to the number and force of the knocks. The perforation b may also be finer or wider, as may be desired.

When the device is out of use, the cover A', 70 the bottom of which is fitted with a small washer c', of felt or the like, against which the point of the cone B' abuts, is placed on the bottom part A, and the powder is then hermetically sealed and free from the influence 75 of air and light.

Although my device has been constructed specially for medical use, it is evident that it will suit equally well for the distribution 80 of any powder, such as spices, salt, &c.

The shape or configuration of the receptacles is immaterial, and they may be cylindrical, flat, square, or polygonal or otherwise shaped in cross-section if they embody the essential features of my invention.

I claim—

1. A distribution-box for powder, consisting of an inner receptacle having an open bottom and a tapering perforated end, and a two-part outer receptacle one part embracing 90 and closing the bottom of the inner receptacle and the other part fitting over and closing the tapering perforated end of the inner receptacle, substantially as described.

2. A distribution-box for powder, consisting of an inner receptacle having an open bottom and a tapering perforated end, of a two-part outer receptacle one part embracing and closing the bottom of the inner receptacle 95 and having a washer interposed between the 100

bottom of the two parts and the other part fitting over and closing the tapering perforated end of the inner receptacle and having a washer arranged to abut against the tapering perforated end, substantially as described.

In testimony whereof I have signed my

name to this specification in the presence of two subscribing witnesses.

JOHAN ALBERT HIOÉG.
